UNITED STATES PATENT OFFICE.

YVES LE BIHAN, OF AMIENS, FRANCE.

INTERNAL-COMBUSTION ENGINE.

1,164,454.

Specification of Letters Patent. Patented Dec. 14, 1915.

Application filed April 19, 1913. Serial No. 762,375.

To all whom it may concern:

Be it known that I, YVES LE BIHAN, a citizen of the Republic of France, and residing at Amiens, in the Republic of France, have 5 invented certain new and useful Improvements in Internal-Combustion Engines, of which the following is a specification.

This invention has reference to two cycle engines of the kind in which there are two 10 neighboring cylinders, each of which has an increased diameter at its lower part, which lower part of the cylinder has to serve as a compression pump for feeding the neighboring cylinder. Each cylinder is 15 therefore composed of a main or power cylinder and a compression pump cylinder.

This invention is characterized in that each compression pump feeds the neighboring main cylinder and that the feeding is 20 by way of openings in the lower part of the main cylinder forming the upper part of the compression pump, a common distribution chamber into which the said openings lead, a horizontal wall in the said chamber 25 for separating the said openings and admission ports arranged in the wall of the motor cylinders, and dividing the distribution chamber into an upper and lower division, two openings in the said horizontal 30 wall, a vertical partition in the form of between the said openings in the lower distribution chamber, another vertical partition in the form of between the said openings in the upper division of the said 35 chamber, openings at the lower part of the cylinders for admitting the explosive mixture and a slot arranged in each motor piston for communicating the said carburetor with each one of the compression pumps.

40 I will now describe my invention with reference to the accompanying drawing, in which:—

Figure 1 is a vertical section of a pair of cylinders of the two-cycle engines embodying the features of the present invention. Figs. 2 and 3 are corresponding sections along the lines A—A and B—B of Fig. 1. Fig. 4 is a vertical section along the line C—C of Fig. 3.

50 In the two cycle engine forming the subject-matter of the present invention that part of the cylinder having the greater diameter forms the compression pump and the cylinders are arranged in pairs at the side of

each other so that the compression pump 55 formed by each of them feeds the neighboring motor cylinder. The engine will thus be formed by a certain number of pairs of cylinders arranged at the side of each other.

The motor cylinders *a* are provided on 60 their walls with two series of opposite ports *b*, *b'*, *c*, *c'*, the ports *b*, *b'* serving for the admission of the explosive mixture compressed by the pump *e* of the adjoining cylinder, and the others *c*, *c'* serving for the 65 exhaust of the gases after having worked in the corresponding motor cylinder *a*. A deflector *f* is provided on the motor piston *d* so as when admitting the fresh gases to prevent them escaping directly through the 70 exhaust ports *c*, *c'* which are at this moment uncovered. The admission ports *b*, *b'* of each cylinder respectively open out into the chambers *g*, *g'* (Fig. 2) formed by the walls of the said cylinders and a casing *h* and 75 together constituting a distribution chest. This chest has a floor *i* which divides it into two stages, into one of which open out as indicated the admission ports *b*, *b'* of the motor cylinders, whereas in the other stage 80 are arranged openings *j*, *j'* communicating with the cylinders *e* of the compression pumps. Furthermore at the base of the main or motor cylinders *a* openings *k* are 85 formed each communicating with the cylinder *e* of the corresponding pump by means of a channel *l* formed in the piston.

Each stage of the chest is subdivided into two compartments, the upper ones *g*, *g'* which correspond to the admission ports 90 *b*, *b'* are separated by a vertical partition *l'* (Fig. 2) thus forming a vertical channel on either side of the partition opening out into the floor *i*, through the openings *m*, *m'*. The lower chambers *n*, *n'* are also separated 95 by a vertical partition *o* which forms a vertical channel on either side, the openings of which in the floor *i* correspond to those *m*, *m'* of the upper channel; but this partition *o* is arranged so that the vertical channel 100 of the chamber *g* is connected up to that of the chamber *n'*, whereas the channel of the chamber *g'* corresponds to that opening out into the chamber *n*. As on the lower floor 105 of the chest openings *j*, *j'* are formed connecting each pump to the corresponding chamber *n*, *n'*, it will be seen that by this simple arrangement each compression pump

e can be made to communicate with the neighboring motor cylinder *a*. The compression pumps *e* are fed on the other hand through openings *k* which open out into a chamber *p* connected to the carburetor and a packing segment *r* forms a joint around the piston *d* between the motor cylinder *a* and that of the compression pump. In these conditions the working is as follows. The cranks 10 of the pistons *d* of each pair of cylinders are arranged at 180°. In the position shown the piston on the left is near the end of its stroke, that is to say the explosive mixture having worked in the cylinder *a* escapes through the ports *c* which the motor piston 15 *d* has uncovered. The admission takes place and the burnt gases are driven out. Indeed at this moment the explosive mixture has been compressed by the pump on the right belonging to the adjoining chambers *n'* and when the ports *b* have been uncovered the 20 fresh gas enters the cylinder *a* for finishing the scavenging of the burnt gases and forming the working charge.

25 During the expansion it will be seen that the piston on the left before reaching the end of the descending stroke, has uncovered the opening *k* and by means of the channel *l* has caused the cylinder *e* of its 30 pump to communicate with the chamber *p* which communicates with the carburetor. The ports *b'* of the other cylinder are closed inasmuch as the corresponding piston has not passed beyond its half stroke. The suction which is produced in the cylinder *e* of the pump consequently occasions the introduction of the explosive mixture.

35 As the piston is working at a certain speed and has occasioned a definite degree 40 of vacuum in the cylinder *e* of the pump and in each of the chambers *g*, *n'*, there results a suction action assuring the complete charging of the cylinder.

45 What I claim as my invention and desire to secure by Letters Patent of the United States is:

50 1. A two-stroke cycle engine having two neighboring cylinders, each of which has two different diameters dividing the cylinder into a motor or power cylinder and a compression pump cylinder with openings in the lower part of the power cylinder constituting the upper part of the compression pump, a common distribution chamber into 55 which lead the said openings, and a horizontal wall in the said chamber to separate the said openings and the admission ports in the walls of the motor cylinders.

60 2. In a two stroke cycle engine with two neighboring cylinders each of which has two different diameters dividing the cylinder into a power cylinder and a compression pump with openings in the lower part of the power cylinder constituting the upper 65 part of the compression pump, a common

distribution chamber into which lead the said openings, a horizontal wall in the said chamber for separating the said openings and the admission ports in the wall of the motor cylinder, two openings in the said horizontal wall, and a vertical partition between the said openings on either side of the horizontal wall for communicating the compression pumps with the neighboring motor cylinders.

75 3. In a two stroke cycle engine with two neighboring cylinders, each of which has two different diameters dividing the cylinder into a power cylinder and a compression pump with openings in the lower part of the power cylinder constituting the upper part of the compression pump, a common distribution chamber into which lead the said openings, a horizontal wall in the said chamber for separating the said openings and the admission ports provided in the wall of the motor cylinders, two openings in the said horizontal wall, and vertical partitions between the said openings on either side of the horizontal wall so as to separate the upper and lower divisions of the said distribution chamber into two separate spaces for communicating the compression pumps with the neighboring motor cylinders.

80 4. In a two stroke cycle engine with neighboring cylinders each of which has two different diameters dividing the cylinder into a power cylinder and a compression pump with openings in the lower part of the power cylinder constituting the upper part of the compression pump, a common distribution chamber into which lead the said openings, a horizontal wall in the said chamber to separate the said openings and the admission ports arranged in the wall of the motor cylinders, two openings in the said horizontal wall, a vertical partition in the form of   between the said openings in the lower division of the distribution chamber, and a vertical partition in the form of   between the said openings in the upper division of the said chamber to communicate the compression pumps with the neighboring motor cylinders.

85 5. In a two stroke cycle engine with neighboring cylinders, each of which has two different diameters dividing the cylinder into a power cylinder and a compression pump with openings in the lower part of the power cylinder constituting the upper part of the compression pump, a common distribution chamber into which lead the said openings, a horizontal wall in the said chamber for separating the said openings and the admission ports arranged in the wall of the motor cylinders, two openings in the said horizontal wall, a vertical partition in the form of   between the said openings in the lower division of the dis-

tribution chamber, another vertical partition in the form of between the said openings in the upper division of the said chamber, an opening at the lower part of each power cylinder for admitting an explosive mixture and a channel arranged in each motor piston for connecting the last-named opening with the compression pump.

In testimony whereof I have hereunto signed this specification this tenth day of 10 April, 1913.

YVES LE BIHAN.
